US00D961118S

(12) **United States Design Patent** (10) Patent No.: **US D961,118 S**
(45) Date of Patent: **** Aug. 16, 2022**

(54) **CEILING PANEL**

(71) Applicant: **Hunter Douglas Industries B V**,
Rotterdam (NL)

(72) Inventors: **Michiel Langeveld**, Rotterdam (NL);
Ralph Steenbergen, Rotterdam (NL)

(73) Assignee: **Hunter Douglas Industries B.V.**, El
Rotterdam (NL)

(**) Term: **15 Years**

(21) Appl. No.: **35/511,059**

(22) Filed: **Dec. 15, 2020**

(80) **Hague Agreement Data**

Int. Filing Date: **Dec. 15, 2020**

Int. Reg. No.: **DM/211857**

Int. Reg. Date: **Dec. 15, 2020**

Int. Reg. Pub. Date: **Jan. 1, 2021**

(30) **Foreign Application Priority Data**

Jun. 30, 2020 (EM) 008026751
